United States Patent

Des. 235,683
Patented July 1, 1975

235,683

PORTABLE RADIO

Hiroshi Hirasa, Osaka, Japan, assignor to Matsushita
Electric Industrial Co., Ltd., Kadoma, Japan

Filed Aug. 16, 1973, Ser. No. 389,036

Claims priority, application Japan Feb. 16, 1973

Term of patent 14 years

Int. Cl. D14—03

U.S. Cl. D56—4 B

FIG. 1

FIG. 2

FIG. 1 is a front, top and right side perspective view of a portable radio showing my new design; and

FIG. 2 is a rear, bottom and left side perspective view.

Portions of the figures are shaded to indicate contrast in appearance, and a portion of FIG. 1 has been diagonally lined to indicate transparency.

I claim:

The ornamental design for a portable radio, as shown and described.
